C. Adams

United States Patent Office.

CALVIN ADAMS, OF PITTSBURG, PENNSYLVANIA.

Letters Patent No. 66,769, dated July 16, 1867; antedated July 9, 1867.

IMPROVED SOAP-DISH.

The Schedule referred to in these Letters Patent and making part of the same.

TO ALL WHOM IT MAY CONCERN:

Be it known that I, CALVIN ADAMS, of the city of Pittsburg, in the county of Allegheny, and State of Pennsylvania, have invented a new and improved Soap-Dish; and I do hereby declare the following to be a full, clear, and exact description thereof, reference being had to the accompanying drawings, making a part of this specification.

Figure 1 is a perspective, showing the bottom, side or rim, projecting lugs, and openings.

Figure 2 is a side sectional view, and

Figure 3 is a section, showing the rim, openings, and lugs.

Like letters refer to like parts in all the drawings.

The object of this invention is to provide a durable, convenient, and cheap soap-dish, which can be attached to a tub, bucket, pail, or other vessel used in washing or scrubbing. I usually make them of cast iron. The size and shape of these soap-dishes may of course be varied to suit the taste of the manufacturer or the demands of the trade.

The one shown in the drawings is triangular or scoop-shaped; the bottom E about three and a half inches in width and about three inches in projection, with the side or rim C rising an inch or more from the base and tapering to the outer edge of the dish, as shown in the drawings. The rim may be extended around the dish, however, if preferred, care being taken to give the pattern sufficient bevel, when they are made of cast iron, to make it draw. On the bottom E of the dish are three lugs or projections, A A A, of convenient length, say from one to two inches, placed near the angle formed by the bottom E and the side or rim C. The centre lug is about half an inch in front of the others, and thus forms a wedge-shaped space between them, so that in placing the dish on the vessel the outer lugs will be inside the vessel and the centre lug outside. By this arrangement it will be seen that the dish always accommodates itself to the different thicknesses of the vessels used, and is firmly held in its place. Two lugs or pins placed opposite or nearly opposite to each other might be made to hold the dish, but would not do it so securely. A pin or lug and screw might also be used for this purpose, but would be more expensive and not so convenient. In making my patterns for the cast-iron soap-dish I cut away the metal from the angle where the bottom E and rim C are joined together, so as to form an opening or openings, D, for the water to drain off from the soap and run down into the vessel, as shown in the drawings, figs. 1 and 3, thereby preserving the soap from waste and filth. If the dish is made from other material than cast iron, the openings can be cut in the manner most convenient and appropriate. The cast-iron dishes are moulded from patterns in the manner well known to all manufacturers, two or four or more of them being attached together in "cards" for increased facility of moulding and casting.

Having thus described the nature, use, and method of constructing my invention, what I claim as new, and desire to secure by Letters Patent, is—

1. A soap-dish, with two or more lugs or pins projecting from the bottom or edge of the dish in the manner substantially and for the purpose shown and described.

2. As an article of manufacture, a cast-iron soap-dish, substantially as shown and described.

CALVIN ADAMS.
